DESIGN FOR A JACK

Gothard G. Hein, Waukesha, Wis., assignor to Hein-Werner Motor Parts Corporation, Waukesha, Wis., a corporation of Wisconsin

Application August 16, 1934, Serial No. 52,963

Term of patent 7 years

To all whom it may concern:

Be it known that I, Gothard G. Hein, a citizen of the United States, residing at Waukesha, in the county of Waukesha and State of Wisconsin, have invented a new, original, and ornamental Design for a Jack, of which the following is a specification, reference being had to the accompanying drawing, forming a part thereof.

In the drawing:—

The single figure is an isometric view of my jack.

I claim:—

The ornamental design for a jack, as shown.

In witness whereof I hereunto subscribe my name this 10th day of August, 1934.

GOTHARD G. HEIN.
